UNITED STATES PATENT OFFICE.

GEORGE H. CAMPBELL, OF TORONTO, ONTARIO, CANADA.

PROCESS OF PREPARING FLAX.

1,086,273.

Specification of Letters Patent. Patented Feb. 3, 1914.

No Drawing.

Application filed March 11, 1910. Serial No. 548,702.

To all whom it may concern:

Be it known that I, GEORGE H. CAMPBELL, a citizen of Canada, and a resident of Toronto, in the county of York and Province 5 of Ontario, Canada, have invented certain new and useful Improvements in Processes of Preparing Flax, of which the following is a specification.

This invention relates to the preparation 10 of flax from flax stalks, to be used in the textile, paper making, and other industries and consists essentially in applying ozonized air to the material, both for the purpose of loosening the incrusting or shive 15 material, and also for the purpose of bleaching the resulting fiber to any desired extent, all as now will be explained, reference being had to the following specification and claims.

20 To carry this process into effect, flax stalks may be treated at any stage after cutting either with or without previous drying and also with or without a previous partial separation of shives. The material may 25 also be treated while immersed in water or other suitable liquid or it may be treated without such immersion, being in the latter case however confined in a closed space.

While the material is immersed in water 30 or other suitable liquid such as a very dilute solution of an alkaline carbonate, or bicarbonate or other equivalent chemical, a stream of ozonized air, obtained by the use of any ordinary existing form of ozonizing apparatus is passed through the liquid. The operation is continued until the incrusting matter or shive material becomes sufficiently brittle to be readily disintegrated and separated from the fibrous material to 40 which it adheres. The operation may also be continued until the fiber becomes more or less bleached so as to be available for use without any other bleaching operation. Where a perfectly white fiber is desired the 45 first operation is carried on only until the shive material is loosened and then the material is dried and subjected to various mechanical operations such as breaking, scutching, hacking, spinning, and weaving, after 50 which the resulting material may again be subjected to the action of ozonized air either while it is suspended in a liquid or suspended in the air in a closed chamber in

which it is slightly moistened by spraying during the operation of bleaching. The operation of loosening the shive material or retting may also be carried on in the latter way, *i. e.*, while the material is being suspended without immersion in a liquid, and is moistened by spraying from time to time 60 while the ozonized air is passed through the chamber. In either case the containing vessel is provided with an outlet for the air which has been used. After the shive material has been loosened, the flax treated is 65 subjected to the various mechanical operations of breaking, scutching, etc. If the material has been converted into yarn or cloth before retting, it is after the treatment of ozonized air dried and subjected to mechanical manipulation by being passed through a breaking machine provided with rollers having very fine corrugations or teeth, or the material may be beaten by suitable machines and passed between revolving 70 brushes or buffing wheels to remove disintegrated shive particles. In place of immersing the material in water or spraying it with water, other suitable liquids may be 75 used such as weak solutions of alkaline hydrates or carbonates.

This process has the advantage over other processes by means of which flax of high grade is produced, in that it is quicker, is 80 capable of being kept under perfect control, is more economical and produces a greater portion of finished flax. The 85 bleaching action is also thorough and quick, resulting also in increased tensile strength, flexibility and luster of the fiber.

When the flax is prepared for the making of high grade linen paper, dried flax stalks may first be broken, the broken material scutched and hacked and then subjected to the action of the ozonized air until the process of retting is completed, or until the material is both retted and bleached, when it 95 is immediately ready for use in the paper making industry.

It is evident that the material may first 100 be immersed in water through which ozonized air is passed and afterward treated while suspended in a chamber without immersion, or vice versa, without departing from the spirit of the invention. When the 105 flax material is suspended in a closed cham-

ber without immersion, the ozonized air used may be first passed through water before it reaches the treating chamber, in which case the spraying with water or other liquid may be dispensed with.

What I claim as new is:

1. In the art of preparing flax, the improvement which consists in subjecting un-retted flax material to the action of ozonized air within a confined space, continuing the operation until the material is retted, and then separating shive material from the fibers.
2. In the art of preparing flax, the improvement which consists in immersing un-retted flax material in an aqueous liquid, passing ozonized air through the liquid, continuing the operation until the material is retted, and then separating shive material.
3. In the art of preparing flax, the improvement which consists in immersing un-retted flax material in alkaline solution, passing ozonized air through the liquid, continuing the operation until the material is retted, and then separating shive material.
4. In the art of preparing flax, the improvement which consists in breaking un-retted flax stalks, subjecting the broken material to the action of ozonized air, continuing the operation until the material is retted, and then separating shive material.
5. In the art of preparing flax, the improvement which consists in breaking un-retted flax stalks, immersing the broken material in an aqueous liquid, passing ozonized air through the liquid, continuing the op-

eration until the material is retted, and then separating shive material.

6. In the art of preparing flax, the improvement which consists in breaking un-retted flax stalks, immersing the broken material in a liquid having an alkaline reaction, passing ozonized air through the liquid, continuing the operation until the material is retted, and then separating shive material.

7. In the art of preparing flax, the improvement which consists in converting un-retted flax material into yarn, immersing the yarn in an aqueous liquid, passing ozonized air through the liquid until the material is retted, and then separating shive material.

8. In the art of preparing flax, the improvement which consists in converting un-retted flax fiber into yarn, immersing the yarn in an alkaline solution, passing ozonized air through the solution, continuing the operation until the material is retted, and then separating shive material.

9. In the art of preparing flax, the improvement which consists in converting un-retted flax fiber into yarn, subjecting the yarn to the action of ozonized air, continuing the operation until the material is retted and then separating shive material.

Signed at New York in the county of New York and State of N. Y. this 18th day of May A. D. 1909.

GEORGE H. CAMPBELL.
